UNITED STATES PATENT OFFICE

2,371,435

VISE

Louis C. Galorneau, Detroit, Mich.

Application December 22, 1942, Serial No. 469,835

1 Claim. (Cl. 81—41)

The present invention relates to new and useful improvements in vises, particularly for holding tools while they are being ground, milled or drilled at various angles, although it will be understood, of course, that the device may be used for any other purpose for which it may be found adapted.

The primary object of the invention is to provide, in a manner as hereinafter set forth, a vise of the aforementioned character embodying novel supporting means which is capable of universal adjustment whereby the tool or other object may be firmly held in any desired position.

Other objects of the invention are to provide a universally adjustable vise of the character described which will be comparatively simple in construction, strong, durable, highly efficient and reliable in use, compact, and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view in side elevation of a vise constructed in accordance with the present invention.

Figure 2 is a top plan view.

Figure 3 is a view in vertical longitudinal section, taken substantially on the line 3—3 of Figure 2.

Figure 4 is a view in end elevation of the device.

Figure 5 is a cross sectional view, taken substantially on the line 5—5 of Figure 1.

Figure 6 is a top plan view of the lower substantially segmental socket member.

Figure 7 is a plan view of the base.

Figure 8 is a bottom plan view of the substantially segmental upper socket member.

Figure 9 is a detail view in plan of one of the locking elements.

Figure 10 is a detail view in perspective of one of the removable jaw faces.

Figure 11 is a detail view in end elevation of the internally threaded bushing in which the slidable jaw actuating screw is mounted.

Referring now to the drawings in detail, it will be seen that the embodiment of the invention which has been illustrated comprises an elongated base 1 of suitable metal. The end portions of the base 1 have formed therein longitudinal slots 2

for the reception of securing elements. The base 1 further includes a circular opening 3.

5 Mounted for rotary adjustment in a horizontal plane on the base 1 is a substantially segmental ball socket 4. The socket 4 includes a depending circular portion 5 which is rotatably engaged in the opening 3 in the base 1, said portion 5 having a circumferentially extending groove 6 therein. Pins or bolts 7 are mounted transversely in the base 1 and engaged in the groove 6 for rotatably securing the socket 4 on said base. A set screw 8 in the base 1 secures the socket 4 in adjusted position. As illustrated to advantage in Figure 6 of the drawings, the socket 4 has formed therein a groove 9. Mounted in the groove 9 and projecting therefrom is a key 10. Countersunk screws 11 secure the key 10 in position.

10 Mounted for oscillating adjustment in the socket 4 in a vertical plane of the key 10 is a ball 12. The ball 12 has formed in its lower portion a substantially T-shaped slot 13. The narrow outer portion of the substantially T-shaped slot 13 accommodates the key 10. Slidably mounted in the relatively wide inner portion of the slot 13 is a locking block 14. A bolt 15 is threaded into the block 14 for retaining said block in position and for locking the ball 12 in adjusted position in the socket 4. The bolt 15 is rotatable in the socket 4 and the key 10. The slot 13 includes an end portion 16 of uniform width for the insertion and removal of the block 14.

15 The upper portion of the ball 12 has formed therein a T slot 17 which extends at right angles to the slot 13 and which is similar thereto. Mounted for peripheral adjustment on the upper portion of the ball 12 is a substantially segmental upper socket 18. As best seen in Figure 8 of the drawings, the socket 18 has formed therein a groove 20. An arcuate key 21 is secured by countersunk screws 22 in the groove 20 and projects therefrom for operation in the narrow outer portion of the slot 17.

20 Slidably engaged in the comparatively wide inner portion of the slot 17 is a locking block 23 which is substantially similar to the member 14. A bolt 24 is rotatably mounted in the socket 18 and the key 21 and threaded to the block 23 for frictionally clamping said block in the slot 17, thus locking the socket 18 in adjusted position on the ball 12. The socket 18 further includes an upstanding, circular portion 25 having a peripheral groove 26 therein.

25 A vise unit 27 is mounted for rotary adjustment on the socket 18. Toward this end, the

unit 27 comprises a bed 28 which rests on the socket 18, said bed having formed in its lower face a circular chamber 29 which rotatably accommodates the portion 25 of said socket 18. Transverse pins or bolts 30 in the bed 28 are engaged in the groove 26 for rotatably securing the unit 27 on the socket 18. An opening 31, which communicates with the chamber 29 in the bed 28, permits access to be had to the slotted head of the bolt 24. Any suitable means may be provided for releasably securing the bed 28 in adjusted position on the socket 18.

The unit 27 further comprises an upstanding stationary jaw 32 on one end portion of the bed 28. Rising from the other end portion of the bed 28 is a longitudinally extending eye 33. A flanged, internally threaded bushing 34 is secured by a set screw 35 in the eye 33. Threadedly mounted in the bushing 34 is a clamping screw 36. The screw 36 is rotatably connected at one end, as at 37, to a slidable jaw 38 on the bed 28. The stationary and slidable jaws 32 and 38, respectively, are provided with removable faces 39.

It is thought that the operation of the device will be readily apparent from a consideration of the foregoing. Briefly, the tool or other device is placed in the unit 27 and firmly secured between the jaws 32 and 38. Then, by loosening any or all of the elements 8, 15, 24, et cetera, the vise may be expeditiously adjusted as desired for holding the tool in any desired position. Scales 40 on the relatively movable members or units facilitate rapid and accurate adjustment of the vise for holding the tool or other object in any desired position or at any suitable inclination.

It is believed that the many advantages of a vise constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

What is claimed is:

A vise comprising a flat horizontal base adapt-

ed to be secured on a support and having a relatively large circular opening, a segmento-spherical ball socket having a disk-like depending circular portion at one end rotatably fitted and secured in said opening of the base, means to releasably secure the socket in rotatably adjusted positions relative to the base, a solid spherical ball seated on said socket and having a peripheral T-shaped groove in the lower portion thereof located in a vertical plane intersecting the axis of the ball, an arcuate key carried by the socket and slidably engaged in the narrow outer portion of said groove to permit oscillating adjustment of the ball relative to the socket about a horizontal axis, a locking block slidably mounted in the wider inner portion of said groove, an inclined bolt rotatably extending through the socket and the key at one side of the lower portion of said ball and threaded into said locking block for releasably binding the latter against the outer walls of the wider portion of said groove to secure the ball in adjusted positions relative to the socket, said ball having a second peripheral T-shaped groove in the upper portion thereof located in a plane intersecting the axis of the ball at right angles to the first-named groove, a second segmento-spherical socket mounted on top of the ball and having an outwardly projecting disk-like portion, a second arcuate key carried by said second socket and slidably engaged in the narrow outer portion of said second groove, a second locking block slidably mounted in the wider inner portion of said second groove, a second bolt rotatably extending through said second socket and said second key centrally of the disk-like portion of said second socket and threaded into the second locking block to releasably bind the latter against the outer walls of the wider portion of the second groove to secure the second socket in adjusted positions relative to the ball, and a vise unit including a jaw-carrying bed having a circular opening in which the disk-like portion of the second socket is rotatably secured to permit rotary adjustment of said vise unit relative to the second socket.

LOUIS C. GALORNEAU.
